UNITED STATES PATENT OFFICE.

PATRICK C. FLANAGAN, OF NEW YORK, N. Y.

INDIVIDUAL PROTECTIVE ARMOR.

1,238,120.

Specification of Letters Patent. Patented Aug. 28, 1917.

Application filed May 26, 1917. Serial No. 171,168.

To all whom it may concern:

Be it known that I, PATRICK C. FLANAGAN, a citizen of the United States of America, residing at the borough of Manhattan, city, county, and State of New York, have invented certain new and useful Improvements in Individual Protective Armor, of which the following is a specification, reference being had to the accompanying drawings.

This invention relates to improvements in individual protective armor designed to be worn by a soldier on the field of battle and to afford him protection against missiles thrown by the enemy, such as bullets from small-arms and machine-guns, shrapnel bullets, pieces of an exploded shell and the like. An object of this invention is to provide armor of the character hereinbefore mentioned which will be simple in construction and efficient and convenient in use.

In the drawings illustrating the principle of this invention and the best mode now known to me of applying that principle, Figure 1 is a front elevation of the armor; Fig. 2 is a side view of the same; Fig. 3 is a central vertical section of the armor shown in Fig. 1; Fig. 4 is a plan of the armor; and Fig. 5 is a horizontal section 30 on the line 5—5 of Fig. 1.

The armor consists of two principal parts, namely, the head armor or helmet and the body armor. The body armor *a* comprises a one-piece plate *b* of suitable metal (that is, metal that combines lightness with great resistance to penetration). From its vertical midline, each side of this plate *b* is bent back (or rearwardly inclined) through an angle of about thirty degrees (Fig. 4) so that a bullet coming directly from the front will be likely to glance off the plate *b*. At the top of each of its sides, the plate *b* is formed with a laterally-projecting shoulder-piece *c* that fits over the soldier's shoulder and protects the same. Each shoulder-piece *c* is formed, in its lower front edge (Fig. 1) with a recess *c'* adapted to permit the soldier to raise his arms (e. g., in aiming his piece, throwing bombs and the like). On the inside of the plate *b* and near the top thereof (Fig. 3), each side of the plate is provided with a loop *d* that is brazed or welded to the plate *b* and is adapted to receive the end *d''* of the curved upper part 55 of an upright crook-shaped supporter *e*, which is thus hingedly attached to the body-

plate *b*. Each supporter *e* is provided with a series of eyes *e'* arranged one above the other. Each side of the plate *b* is also provided with a vertically-extending series of eyes or loops *d'''*, *d''*, secured to the inside of the plate *b*, as by brazing or welding. In each of the eyes *d'''*, there is fastened one end of a body-strap *f* that is passed horizontally through a pair of the eyes *e'* carried by the upright parts of the supporters *e* and the other end of which is formed with holes adapted to receive the tongue *g''* of a buckle *g'* carried by one end of a strap *g* the other end of which is fastened to one of the eyes or loops *d''*. By pulling the straps *f* taut, the body-plate *b* may be fastened to the body *h* of the soldier and then secured by the buckles *g'*. To provide a cushion between the body-plate *b* and the body *h* of the soldier, whereby the shock of impact of the missiles that strike against the body-plate *b* may be absorbed, there is secured to each side of the plate *b* on the inside thereof a vertically-arranged series of 60 looped or bow-shaped leaf-springs *i* an end of each of which is formed with a slot *i'* so that the springs *i* may yield or give markedly in case of necessity, the shank of a fastening stud *i''* passing through the slot 65 *i'*. The loop or swell portions of the springs *i* of each series (or side of the plate *b*) are adapted to bear against the body *h* of the wearer (Fig. 5) and are connected by means of a stiffener or upright *j*, which serves to 70 cause the springs *i* of the series to act in unison.

The head-covering or helmet *k* is dome-shaped and is formed with a circularly-arranged horizontal series of narrow slits *k'* 75 through which the soldier sees. This helmet *k* is revolubly mounted in the following manner (Fig. 3): To the upper part of the body-plate *b*, there is fastened, as by riveting, an annular band *m* that is L-shaped in 80 vertical section and is formed with a horizontally-disposed inwardly-projecting annular flange *m'* that serves as a runway for the steel balls *n*. Near its lower edge, the helmet *k* is formed with an outwardly-extending annular flange or rib *k''* that rests on the balls *n*. In order to exclude foreign matter as far as is practicable, the upper edge of the band *m* is turned inwardly over the annular rib *k''* and the lower edge *k''* 85 of the helmet *k* is turned outwardly under the annular flange *m'*. As shown in Figs. 1 90

to 3, the slits k' are inclined somewhat to the vertical, whereby danger of penetration of the helmet k by a bullet is lessened somewhat. Since the helmet k is revolvably mounted, it will tend to spin around on the balls n , when struck by a bullet and the latter will tend to glance off the helmet and danger of penetration by the bullet is thus reduced. When the body-plate b is fastened 10 in place, it will be found that the soldier's arms, when hanging by his sides, will be protected by the sides of the plate b , since enough room or space will be left for the soldier's arms within the body-plate b , when 15 the straps f have been drawn taut.

I claim:

1. A military protective armor including a body-plate and a helmet revolvably mounted thereon and free from screw connection therewith.

2. An individual military protective armor including a V-shaped body-plate; and a vertically-arranged series of horizontally-disposed bow-shaped leaf-springs mounted 25 on the inside of each side of said body-plate and spaced from one another, the swell part of each of said springs being adapted to bear against the body of the wearer to produce a cushioning effect.

3. An individual military protective armor including a body-plate; and a vertically-arranged series of horizontally-disposed bow-shaped leaf-springs mounted on the inside of said body-plate, the swell part 30 of each of said springs being adapted to bear against the body of the wearer and one end

of each of said springs being loosely attached to the body-plate to produce a cushioning effect.

4. An individual military protective 40 armor including a body-plate; a vertically-arranged series of horizontally-disposed bow-shaped leaf-springs mounted on the inside of said body-plate, the swell part of each spring being adapted to bear against 45 the body of the wearer; and an upright stiffener fastened to the swell parts of said springs to produce combined action of the same.

5. An individual military protective 50 armor including a body-plate; upright crook-shaped supporters for supporting said body-plate upon the shoulders of the wearer, said supporters being fastened at their upper end to the inside face of the body-plate; and horizontally-disposed body-55 straps carried by said supporters for fastening the body-plate to the body of the wearer.

6. An individual military protective armor including a body-plate; and a helmet 60 revolvably mounted thereon, said helmet being formed with a series of narrow slits arranged on a substantially horizontal arc.

Signed at the borough of Manhattan, city, county and State of New York, in the presence of the two undersigned witnesses, this 65 twenty-third day of May, A. D. 1917.

PATRICK C. FLANAGAN.

Witnesses:

GEORGE E. BROWN,
JAMES HAMILTON.
